UNITED STATES PATENT OFFICE.

CHARLES HILL, OF PHOENIX, BRITISH COLUMBIA, CANADA.

DRAWING INSTRUMENT.

1,039,057.

Specification of Letters Patent. Patented Sept. 17, 1912.

Application filed November 23, 1909. Serial No. 529,614.

To all whom it may concern:

Be it known that I, CHARLES HILL, a subject of the King of Great Britain, residing at Phoenix, in the Province of British Columbia and Dominion of Canada, have invented new and useful Improvements in Drawing Instruments, of which the following is a specification.

This invention relates to drawing instruments, and its object is to provide a device which may be set at any angle and which carries at one of its ends, a compass or circling pencil, so that circles or grooves may be struck on centers arranged at any angle from a given point.

The device is adapted to be attached to a drawing board and is especially useful in laying out gear wheels and similar designs as will be more fully described in the following specification, set forth in the claims and illustrated in the drawings, wherein:

Figure 1 is a plan view of the instrument. Fig. 2 is a sectional view on the line 2—2, of Fig. 1. Fig. 3 is a sectional view on the line 3—3. Fig. 4 is a sectional view on the line 4—4. Fig. 5 is a sectional view on the line 5—5. Fig. 6 is a sectional view on the line 6—6. Fig. 7 is a detail view.

The instrument consists of a base piece 10 having a plate with perforations 11 at each end by which it is attached to the drawing board and if necessary upon the sheet of drawing which is in state of preparation. This base piece has along its length, the grooves 12 in which slides a block 13 with a threaded stud 14 inserted therein before the ends of the base 10 are added and carrying a nut 15 and between the nut and the block is located a plate 16 with grooves in its under surface to receive a guide and slotted bar 17. The stud 14 becomes the center for the bar 17 when it is swung around at various angles and this bar may be carried along the base piece 10 to any desired point and locked 45 according to the scale of inches on the surface of the base piece. When the bar 17 is properly located and swung to its desired angle, it may be clamped in that position by means of the plate 16 and the nut 15.

50 At the outer end of the bar 17 is an adjustable block 18 Fig. 5 with a slot 19 Fig. 1 through which plays a threaded stud 20 carried by a sliding plate 21 Fig. 6 on the lower side of the bar and passing through a washer 55 22 on the upper side, the plate and the washer being locked together by means of

toothed nut 23 screwing on the stud and beneath the block 18. At one end of the block 18 is a pencil sharpener 24 with a cutting blade 25 of any well known construction and at the outer end of the block is a socket 26 for the pivot 27 of a circling pencil or pen. The socket 26 has an inner sleeve 28 upon which fits a similar sleeve 29 to which the arm 30 of the circling pencil is attached by means of a thumb screw 31 and near the upper end of the arm 30 is carried, a toothed segment 32 with which is geared a pinion 33 on a thumb nut 34 which is journaled in the arm 35 of the instrument and by this means, the pencil 36 may be adjusted for certain circles or arcs and held there by the pinion. The upper surface of the block 18 has teeth 37 Fig. 7 to receive the studs on the lower side of a plate 40 which is acted on by the nut 41 so that all of these parts connected with the block are held firm and rigid when it is set up in any desired angle for the operation of the pencil 36.

At the rear end of bar 17 and playing in its slot 42 is a threaded stud 43 which is secured to a block 44 that is adapted to slide on the bar and lock to same a slide 45 which straddles the stud and has forward hooked ends or fingers 46 to engage the block 16. The object of this slide and its adjustment is, that it may be set on the block 44 so as to allow a certain amount of play between the forward end of the block and the fingers 46, this play amounting to the pitch or depth of the teeth to be drawn so that when the stud 14 is used as a center, a circle may be struck while the bar is adjusted against the base piece 10 and another circle may be struck while the fingers 46 are rested upon the base piece at the proper distance on the scale.

In order to successfully operate the block 18, its stud 20 may be set at the desired point along the bar 17 and locked there by means of the nut 23. The block is still free to move and when it is swung to the desired point on the stud 20, it is locked at that point by the nut 41 so that circles may be struck by the pencil 36 from the center 27.

It is obvious that in the construction of this device, the details may be modified or otherwise arranged without departing from the essential features above described.

The pencil 36 is held in the socket 47 of the arm 35 by means of a toothed wedge 48 which when in place bears upon the side of

the pencil but releases same when pulled out.

What I claim as new and desire to secure by Letters Patent is:

5. 1. In combination with a base piece adapted to be secured to a board, of a slotted bar secured to the base piece, and an adjustable slotted block with a socket carried at the end of the bar and adapted to receive a circling pen or pencil, a studded plate mounted on the block, the said block having its upper base provided with grooves adapted to receive the studs of the said plate, a bolt extended through the said block and plate, 15 and a nut on the bolt substantially as and for the purpose described.
10. 2. In a drawing instrument, the combination with a grooved base piece adapted to be secured to a board, a sliding block on the same, a slotted bar with a scale, a bolt securing the base piece, the block and the bar together at any desired angle, a sliding plate provided with a stud arranged at the under side of said bar, and a block pivoted 20 on the stud on the upper side of the bar and adapted to carry a circling pen or pencil.
25. 3. In a drawing instrument, the combination with a grooved base piece having perforations in its ends, of a sliding block on the same, a slotted scale bar, a plate carried by the bar, a stud and nut carried by the said block and adapted to clamp the said 30

bar at different points on the base, a swiveled block adjustably mounted on the outer end of the bar, and a circling pen or pencil 35 carried by the said block.

4. The combination with a grooved base piece having a scale and adapted to be secured to a board, of a sliding block carried in the said grooves, a slotted bar with a 40 scale, a stud and nut on the block, a plate adjustable on the bar and adapted to clamp the bar to the said base on adjustment of said nut, a swiveled block at the outer end of the said slotted bar, and a bolt and nut for 45 locking the said block at different points on said bar.

5. The combination with a grooved base piece, of a slotted bar secured to the said base piece, an adjustable block mounted on 50 the said bar and provided with a stud extending through the slot of the bar, a nut for the stud, and a slide mounted on said bar and straddling the said stud and provided with forward hooked ends adapted 55 to engage the end of said block substantially as and for the purpose described.

In testimony whereof I affix my signature in presence of two witnesses.

CHARLES HILL.
